ELECTRIC CONTACT RING FOR KNITTING MACHINES

Michael Wachsman, Brooklyn, N. Y., assignor to
 Wachsman Sons', Inc., a corporation of New
 York

Application April 6, 1940, Serial No. 328,252

2 Claims. (Cl. 66—163)

This invention relates to electric contact rings which are used in knitting machines for conducting electric current to certain parts of the machine. More particularly such rings are used to provide electric contact for so called slack take up devices or end detectors in which a wire arm is held in a normal open circuit position by the travelling yarn. When the yarn breaks or runs out the arm moves into contact with the ring to close the electric circuit which then in known manner causes the knitting machine to stop so the trouble with the yarn can be attended to. The electric circuit is normally open to avoid shocks to the operator. Such contact rings are shown for instance in the U. S. Patents No. 2,147,275, Feb. 14, 1939, and No. 2,168,755, Aug. 8, 1939. The circuit is closed between the contact ring and an arm of the slack take up device hence it is of the utmost importance that both of these elements are kept constantly automatically clean. However, one of the greatest causes of failure to promptly close the circuit is dirt. Floss from the yarn, dust in the machine shop and paraffin in the yarn combine to coat the parts of the machine with an insulating layer which at times is so thick that it can be scraped off. The operators have neither the time nor the inclination to continually wipe these parts to keep them clean. Some means are therefore required whereby the ring and the arm of these devices may be automatically selfcleaning.

The object of this invention is to provide an electric contact ring of novel design and construction which is practically selfcleaning both for itself and for the wire arm and insures prompt good electric contact. It may be stated here that the terms electric contact ring, or contact ring or electric ring are used in the trade to designate the same element to which this invention relates. In the accompanying drawing—

Fig. 1 is a diagrammatic illustration of a stop mechanism for a knitting machine including a contact ring according to this invention.

Fig. 2 shows a portion of the ring.

Fig. 3 is a sectional view of the ring taken on line 3—3 of Fig. 2.

Fig. 4 shows the use of the ring in inverted position.

Fig. 5 is a perspective view of another form of ring.

Figs. 6, 7 and 8 show modifications.

Fig. 1 shows a stationary electric stop mechanism for knitting machines sometimes called a knitting machine top. Its use and the manner in which it is attached to the machine are well

known in the art. The device comprises a central shaft 1 which at the top carries knot detectors 2 which may be of the type shown in the Reissue Patent 19,069, Feb. 6, 1934. Further down and shaft carries end detectors 3 which may be of the type shown in the Patent 1,784,560, Dec. 9, 1930. The yarn bobbins 4 are supported on arms 5. The yarn passes up through the end detectors 3, the knot detectors 2 and then down again through a plate 6 having eyes 7 for the passage of the yarn 16.

The contact ring 8 according to this invention is carried by arms 9 secured to the shaft. The ring is insulated as indicated at 10. Below the ring 8 there is a bracket 11, secured to the shaft which supports slack take up devices each of which consists of an arm 12 with eyelet 13 and a wire spring arm 14 with an eyelet 15. The yarn 16 passes from the plate 6 down through the two eyelets 13 and 15 and thence to the knitting mechanism itself, not shown.

Electric current is supplied to the detector devices and the contact ring in any suitable and well known manner, wires being indicated at 17. The current to the ring is by way of a spring contact finger 18. The other side of the circuit is grounded on the machine. The circuit is normally open at 2 and 3 and also at 14, the slack take up device being insulated from the bracket 11 as indicated at 20. When the yarn breaks or runs out the wire spring 14 snaps upward into engagement with the ring. The circuit is then closed and in usual manner the machine stops. No special discussion of the operation of the detector devices is necessary. They are in daily use and well known to the art.

Heretofore much trouble has arisen from the fact that the contact ring as well as the wires 14 became coated with an insulating layer of dirt and grease so good electric contact could not be had between these parts. Particularly the wire arms were not scraped clean by merely engaging the lower edge of a plain ring. With a contact ring constructed according to this invention such trouble is eliminated. As shown in the drawing the ring 8 is not a usual ring formed from a plain strip of conducting metal which provides only a lower straight edge. The ring 8 is of V-shape in cross section and provided with teeth 21 which preferably are shaped and spaced as shown in Fig. 2. The teeth have inwardly sloping surfaces 22 leading to a restricted channel 23 which in turn leads into an enlarged space 24. Preferably the channel is made of less width than the diameter of the wire arm 14 so that when the latter

snaps up into engagement with the ring, the particles of dirt which are scraped off or become loosened may be thrown into the larger space 24, the wire being caught by the channel. Thus packing or accumulation of dirt is to some extent prevented or at least delayed. However, the main feature of the ring is that the space between the teeth provides four sloping surfaces 22 and if the wire snaps through the channels and into the spaces 24, the sides of the wire have necessarily been scraped not only at four different points but at four different areas because seldom, if ever, do the wires snap straight upward right into the middle of the spaces between the teeth. This is because the wires are not stationary except relative to their immediate support. They sway and vibrate with the machine and respond to the uneven pull of the yarn. At no time therefore will rubbing contact between the sides of the teeth and the wire occur at the same spot in the wire but the scraping occurs along and across the wire. The upper edges of the ring 26 and 27 are straight and provide double contact points for the current feeding finger 18. The latter is looped and springy to provide contact. Braces as at 25 may be used to stiffen the ring.

Fig. 5 shows a V-shaped ring having straight comb teeth 30. This construction also provides a plurality of scraping surfaces 31 spaced along and across the ring. Figs. 6 and 7 show rings which are formed from a plain ring band 32 having teeth 33 and 34 shaped somewhat like those in Fig. 2. The sloping surfaces at 35 in the two figures provide scraping contacts with the wires 14.

The ring may be used inverted as shown in Fig. 4. This figure illustrates a simple type of

end detector. The switch arm 40 is held in normal open position by gravity. When the yarn breaks or runs out, the arm falls forward into engagement with the ring and closes the circuit.

5 The ring 8 as above described may be used in both stationary and rotary knitting machines. Where for some reason the contact finger 18 must engage the ring from below the teeth may be curved as shown at 36 in Fig. 8. The finger 10 will then be wide enough to span several teeth.

With a ring constructed according to this invention it has been found that the contacting wire and the ring are kept automatically clean all the time and the dirt does not accumulate.

15 I claim:

1. An electric contact ring for knitting machines consisting of a ring body V-shaped in cross section, spaced teeth formed in the lower edge of said ring, each side of said V-shaped ring forming an upper straight edge and braces secured between the sides of said ring to stiffen the same.

2. In an electric contacting device for knitting machines including a contact ring and a wire member normally urged into contacting engagement with said ring to close an electric circuit,

25 said wire member being held in normal circuit open position by a travelling yarn, said contact ring being of V-shaped cross section and provided with spaced teeth at its lower edge forming

30 narrow entrance channels for said wire member to pass through into the space at the root of the teeth to contact said ring at several points when said yarn breaks or runs out whereby to

35 provide good rubbing contact between said wire member and the teeth to make the same self-cleaning for the purpose described.

MICHAEL WACHSMAN.
